UNITED STATES PATENT OFFICE.

JOHAN LUDWIG WALDEMAR OLSEN, OF COPENHAGEN, DENMARK.

BAKING-OVEN.

SPECIFICATION forming part of Letters Patent No. 584,645, dated June 15, 1897.

Application filed December 14, 1896. Serial No. 615,563. (No model.)

To all whom it may concern:

Be it known that I, JOHAN LUDWIG WALDEMAR OLSEN, baker, a citizen of the Kingdom of Denmark, residing in Copenhagen, in the Kingdom of Denmark, have invented 5 certain new and useful Improvements in Baking-Ovens, of which the following is a specification.

This invention relates to certain improvements in baking-ovens, and especially to those where the baking takes place in chambers that are heated from the outside by means of a fireplace located in the bottom of the oven.

15 To the baking-oven shown in the accompanying drawings the baking-chambers are surrounded by flues which, after the firing has ceased, still receive heat enough from the fireplace in the bottom of the oven to permit 20 several consecutive bakings without any new firing being necessary.

In the accompanying drawings, Figure 1 is a vertical longitudinal section of the oven. Fig. 2 is a vertical section transversely thereto. 25 Fig. 3 is a horizontal section of the oven, and Fig. 4 is an enlarged detail view of the movable tray.

In order to increase the baking capacity of the oven, the fireplace is provided with an 30 arched top that serves to store part of the heat developed in the fireplace and acts as a heat-accumulator. The products of combustion pass from below upward through the flues surrounding the baking-chambers— 35 viz., through the flues between these chambers—and issue from the oven through the chimney, which is placed on a level with the fireplace.

In the accompanying drawings firing is 40 shown as being effected by means of gas, but of course any other suitable fuel may be used. The products of combustion ascending through flues M in the front part of the oven pass over and then behind the baking-chambers A A' to the outlet K under the fireplace.

45 In order, during the frequent taking out of the baked bread and introducing the unbaked, to prevent the loss of too much heat from the flues surrounding the baking-chambers and also to avoid part of the products of combustion escaping from the flues in the

front part of the oven, the following construction is employed:

The tray B, upon which the bread is placed, is made movable, so that it can be pulled out 55 of the baking-chamber A and again pushed into the same. Care must be taken, however, that when the tray is pulled out it does not intercept the ascending of the products of combustion through the vertical flue in the 60 front part of the oven, and it is further of importance that when the tray is completely pushed in there should be absolutely no communication between the flue M and the outer air, as also between the said flue M and the 65 baking-chamber.

With the foregoing object in view a flue-piece F, either of masonry or any other suitable material, is placed on the front part of the movable tray. When the tray is completely pushed into its place, this flue-piece 70 exactly fits into the mouth of the oven in such a manner that its walls cut off the communication between the outer air and the flue M, as also the communication between this 75 latter flue and the baking-chamber, while at the same time the opening H in the flue-piece forms a communication between the parts of the flue M lying above and below the mouth 80 of the oven.

The rear part of the movable tray is furthermore provided with a vertical closing-plate G of such a shape and size that when the tray is pulled quite out this plate closes the mouth of the oven and thus prevents the heat 85 and the products of combustion from escaping during the time necessary for filling the tray with fresh material to be baked. During that time the ascending products of combustion have free passage through the flue M, so 90 that the firing need not be discontinued.

As shown in Fig. 4, the tray B can be supported by small undercarriages C, provided with wheels D, that can move along rails E.

Other suitable means may of course also be 95 employed for making the movement of the tray easy.

The above-mentioned flue-piece F, instead of being placed upon the movable tray and in firm connection with same, can be arranged 100 independently thereof. In this case the flue-piece is pulled out first and thereafter the

tray. This latter arrangement may be of importance in baking-ovens of large dimensions where the bread placed upon the tray is of a considerable weight.

5 Above the baking-chamber with the movable tray another baking-chamber A' may be arranged, as shown on the drawings, which chamber may be with or without a movable tray. The spaces between the baking-chambers and underneath the lower chamber are connected with the flue in the front part of the oven.

Having thus described my invention, I claim as new and desire to secure by Letters Patent—

15 1. The combination, with a baking-oven, of a movable tray arranged in the baking-chamber, and a flue-piece for closing the mouth of the baking-chamber, substantially as set forth.

20 2. The combination with, a baking-oven provided with flues extending across the mouth of the baking-chamber, of a movable

tray arranged in the baking-chamber, and a flue-piece for closing the mouth of the baking-chamber, and adapted to establish communication between the upper and lower parts of the flues, substantially as set forth. 25

3. The combination with, a baking-oven, of a movable tray arranged in the baking-chamber, a flue-piece at the front end of the tray, and a vertical plate at the rear end of the tray, substantially as set forth. 30

4. The combination with, a baking-oven, and rails in front of the mouth of the baking-chamber, of a movable tray in the baking-chamber, a carriage on which the tray is mounted, and a flue-piece for closing the mouth of the baking-chamber, substantially as set forth. 35

In testimony that I claim the foregoing as my invention I have signed my name in presence of two subscribing witnesses.

JOHAN LUDWIG WALDEMAR OLSEN.
